W. F. ROLSTON.
KNITTING MACHINE.
APPLICATION FILED AUG. 2, 1912.

Patented Mar. 10, 1914.

2 SHEETS—SHEET 2.

UNITED STATES PATENT OFFICE.

WALTER F. ROLSTON, OF ROCKFORD, ILLINOIS, ASSIGNEE TO BURSON MANUFACTURING COMPANY, OF ROCKFORD, ILLINOIS, A CORPORATION OF ILLINOIS.

KNITTING-MACHINE.

1,090,119.

Specification of Letters Patent. Patented Mar. 10, 1914.

Application filed August 2, 1912. Serial No. 712,920.

To all whom it may concern:

Be it known that I, WALTER F. ROLSTON, a citizen of the United States, residing at Rockford, in the county of Winnebago and the State of Illinois, have invented certain new and useful Improvements in Knitting-Machines, of which the following is a specification.

- The object of this invention is to construct a device that shall automatically stop the working of a knitting machine if the feed of the yarn is broken or in any way hindered in its passage from the bobbins to the needles.
- 15 In the accompanying drawing: Figure 1 is a side elevation of the yarn feeding mechanism of a knitting machine. Fig. 2 is a section on the line *a a* of Fig. 5, showing the tripping mechanism in its normal position.
- 20 Fig. 3 is a similar section on the line *a a* of Fig. 5, showing the tripping mechanism having been set off. Fig. 4 is a front view of the feeding mechanism of a knitting machine. Fig. 5 is a fragmentary plan view showing the location of the members that set off the tripping mechanism.
- 25 In the drawings only so much of a knitting machine is shown as is sufficient to explain my invention.
- 30 The machine has a bed 1, a horizontal reciprocating yarn carrier 2, a yarn changer 3, a driving shaft 4 driven by the pulley 5, also carrying the loose pulley 6, and a belt shifter 7 pivoted at 8, all of which are well known
- 35 factors in the construction of knitting machines. Suitably supported on the bed 1 of the machine is the vertical rod or post 9, which forms the main support for the feeding apparatus. Clamped to the post 9 is the
- 40 bracket 10, which has formed at its extremity two oblique jaws 11 and 12, riveted together carrying a plurality of horizontal wires 13, which are held parallel by the auxiliary jaws 14 and 15, also riveted together.
- 45 The adjustable sleeve bracket 16 is clamped to the post 9 above the bracket 10, and carries in its sleeve a horizontal rod 17, which lies parallel to the tension wires 13. Mounted on the rod 17, and carried rigidly
- 50 by a set-screw, is the collar 18, having the extending support 19, on which at its upper extremity is rigidly carried the bolt 20, upon which is pivotally mounted the arm 21, having connection with a spiral spring coiled

about the bolt 20, and the other end fastened thereto, the tension of the spring forcing the arm in a contra-clockwise direction, said arm carrying a wire spring 22, one end of which is held in the arm 21 and the other end having an eye or loop, through which is suspended a spring tension wire 23, one end of which is rigidly secured to the arm 21 and the other carrying an eye or loop. The bolt 24 is fastened rigidly, intermediate the bolt 20 and the rod 17, to the support 19, and carries a spring tension wire 25 coiled thereabout, one end carrying an eye or loop, the other end extending up, forming a narrow V portion 26, the lower end of which has a spring connection 27 with the collar 18, this spring holding the tension wire 25 and its portion 26 in a normal position.

The collar 28, fastened rigidly to the rod 17 by a set-screw, carries a vertical rod 29, being bent just below the collar 28 to a horizontal position, and supports at its extremity a rod 30, which lies horizontal and parallel to the rod 17, and carries a yarn feed stop 34. Pivotedally supported by the collar 28, but on the side opposite to the rod 29, is the rod 31, which lies at an angle parallel to the jaws 11 and 12, and carries a plurality of eyes 32, spaced intermediate the tension wires 13; also to the same pivotal support is secured the upstanding offset rod 33.

Clamped to the post 9 above the bracket 16, is the tripping mechanism, the object of my invention.

The main body portion 35 has pivoted to it a catch member 36 having two oppositely extending arms, which have two straight parallel sides 37 and 38, and two similarly curved sides 39 and 40. Bearing up against the member 36, just a little to one side of the pivot and at the beginning of the curve 40, is the rod 41, having one end beveled and the other end pivotally connected to the belt shifter 7, and which is guided by the slot 42 formed in the frame 35, and which is also held to one end of the slot, as shown in Fig. 2, by the spring 43, which is fastened to the body 35. The horizontal rod 44 is pivotally connected at one end to the body 35, and has its movable end held up against the vertical stationary bar 45, secured to the member 28, said rod 44 being held thus by the bell-crank lever 46, having a weight at its free end. Pivoted to the body 35, is the dog 47, which

is adapted to engage in notches formed in the member 36.

The tripping mechanism is shown in its normal position in Fig. 2, the rod 41 bearing up against the member 36, which is held from revolving by the rod 44, which rests under the outer extremity of the face 36, the dog 47 simply resting inoperative as shown.

The passage of the yarn through the feeding apparatus is as follows: The yarn 48 comes from the spool or bobbin, passes over the wires 13 and through the eyes 32 as shown, thus forming a tension for the yarn; from here the yarn passes through the eye 25 supported by the spring tension wire 25, then passes through the feed stop up through the eye formed by the tension wire 23, and then down to the yarn carrier 2 which feeds the yarn to the needles.

The action of the feeding apparatus is as follows: The knitting machine is driven by any suitable power by the shaft 4, and the yarn carrier 2 holding the yarn 49, a portion of the yarn 48, is reciprocated across the needles, feeding out yarn, and thus drawing the spring tension wire 23 down. Because of the design in the shape of the stockings, less yarn is required at some reciprocations than at others, a portion of the 30 yarn is unused, which slack is taken up by the spring tension wire 23. When the yarn carrier returns, and more yarn is fed out, the spring tension wire 23 will again be drawn down, the yarn being freed from the 35 stop 34, allowing additional yarn to be drawn through the eye carried by the spring tension wire 25, eyes 32, tension wires 13 and from the bobbin. As additional yarn is being drawn, the spring tension wire 23 will 40 rise by the strength of the springs 22 and 23, and the spiral spring fastened to the arm 20, thus pulling the yarn 50, a portion of the yarn 48, above the yarn stop 34, which will then automatically stop the feed of the 45 yarn.

The operation of the tripping mechanism to stop the machine will be seen from the following: Should the yarn in the course of its passage between the bobbins and the 50 feed stop 34, be broken, the tail end of the yarn would either pass through the tension eyes 32, or cause the yarn to become so slack, that the bar 31 would fall to a vertical position, thereby swinging its upper 55 bar 33 into contact with the horizontal rod 44. This contact will swing the rod 44 on its pivot, and thereby it will be disengaged from beneath the surface 37 of the member 36. Since the member 36 is now free, the 60 rod 41 will be raised by the cylindrical weight 53 at the end of the belt shifter 7, shifting the belt to the loose pulley 6, thereby stopping the working of the machine. The member 36 will then assume a vertical 65 position, with the rod 41 held up close to

it by the spring 43, as shown in Fig. 3. When the break in the yarn has been repaired, the rod 41 is brought down as shown in dotted lines in Fig. 3, the spring 43 forcing it to the end of the slot 42; the dog 47 holding the member 36 from any backward movement. The beveled end of the rod 41 will then bear upward against the curved surface 39, and set the member 36 in its normal set position, with the end of the straight surface 38 resting on the horizontal rod 44, which is moved in again by the weight on the bell-crank lever 46. If the feed of the yarn should be stopped in any way, the yarn already in the feeding apparatus would be gradually consumed by the needles, drawing the spring tension wire 25 down until its upstanding portion 26 was swung into contact with the rod 44, and thus the tripping mechanism set off and the machine stopped. If the yarn should be broken at a point between the feed stop 34 and the yarn carrier 2, the spring tension wire 23 would fly up and strike the rod 44, thus setting off the tripping mechanism and stopping the machine.

While in the above description I have described the feeding mechanism of the yarn 48 only, it will be understood that a plurality of feeding apparatus can be carried on the rod 17 and adapted to set off the tripping mechanism in the manner I have described, and I have shown a second such apparatus carrying the yarn 51, whose portion 52 leads to the yarn changer 3. When the design in knitting requires a different yarn, the yarn 52 will be automatically substituted for the yarn 49, the yarn 52 being then held in the yarn carrier 2.

In the construction of tripping devices now in use, the pressure of a rod similar to that of rod 41 against different members, has always, because of the design of such members, been too great for the blow that the members 26 and 33 give on being released to set off the tripping mechanism, even though the weight on the belt shifter be reduced to a minimum, and this causes the machine to continue running when a break occurs, which results in the loss of the stocking being knitted; but it will be readily seen that in the novel construction already described and especially of the bearing point of the rod 41, that the mechanism will be tripped instantly upon the least side thrust on the rod 44.

I claim as my invention:

1. A knitting machine stopping device, comprising a drive stop, a pivoted catch, a rod having a thrust against said catch member at one side of the pivot thereof, a tripping bar adapted to contact said catch at the opposite side of its pivot and to hold the catch in a set position against the action of said rod, and means for releasing said trip-

- ping bar, whereby the catch is released thereby disengaging said rod from its thrust contact with the catch causing the rod to actuate the stopping device.
5. 2. A knitting machine stopping device, comprising a drive stop, a pivoted catch member, a rod having a thrust against said catch member and a connection with the drive stop, a tripping bar adapted to hold the catch in a set position against the action of said rod, means for releasing the tripping bar whereby the catch is sprung and the rod actuated to operate the stopping device, and means for maintaining the catch in its sprung position to allow said rod to be operated independently of the catch to set the rod in its said thrust position when the tripping bar has been returned to its normal position.
10. 10. The catch in a set position against the action of said rod, means for releasing the tripping bar whereby the catch is sprung and the rod actuated to operate the stopping device, and means for maintaining the catch in its sprung position to allow said rod to be operated independently of the catch to set the rod in its said thrust position when the tripping bar has been returned to its normal position.
15. 15. 3. A knitting machine stopping device, comprising a drive stop, a pivoted catch, a vertical rod having an upward thrust against the catch and having a connection with the drive stop, a pivoted horizontal tripping bar adapted to release the catch, means for pivoting the tripping bar thereby allowing the catch to pivot and the vertical rod to rise and operate the drive stop, and a dog adapted to hold the catch from backward movement.
20. 20. 4. A knitting machine stopping device, comprising a drive stop, a pivoted catch having two oppositely extending arms, a vertical rod having an upward thrust against one of the arms, to one side of the pivot and having connection with the drive stop, a pivoted tripping bar adapted to rest under the other arm of the catch and hold the catch from movement, means for pivoting the tripping bar, and a dog adapted to hold the catch from backward movement.
25. 25. 5. A knitting machine stopping device, comprising a drive stop, a pivoted catch, a vertical rod having an upward thrust against the catch and having a connection with the drive stop, a pivoted tripping bar holding the catch in a set position, means for pivoting the tripping bar, thereby releasing the catch and allowing the vertical rod to rise and operate the drive stop, a dog adapted to hold the catch from backward movement, a spring adapted to hold the vertical rod against the catch so that upon the downward movement of the vertical rod, said rod will set the catch in a set position.
30. 30. 6. In a knitting machine stopping device, a pivoted catch, a member having a thrust contact with the catch at one side of the pivot thereof and being connected with a drive stop, means actuatable by defect in the yarn feed and being adapted to hold said catch in a set position, said catch when released by said member, being pivoted to allow the thrust member to move separate from the catch and cause operation of the drive stop, and said catch having a face operable upon by the thrust member when said member has been retracted from said operated movement and again engages the catch in a thrust contact, to move the catch to its set position.
35. 35. In testimony whereof I have hereunto set my hand in presence of two subscribing witnesses.
